United States Patent Office

Des. 228,388

Patented Sept. 18, 1973

228,388

ELECTRIC LIGHT BULB

Jack N. McCarthy, Meadowood Road,
Tolland, Conn. 06084

Filed Oct. 4, 1971, Ser. No. 186,574

Term of patent 14 years

Int. Cl. D26—04

U.S. Cl. D26—8

FIG. 2

FIG. 1

FIG. 1 is an elevational view of an electric lamp bulb showing my new design.

FIG. 2 is a top view thereof.

The characteristic feature of my design resides in the specific configuration of the lamp envelope which is formed as a screw thread.

I claim:

The ornamental design for an electric light bulb, as shown and described.
